DRIVING ATTACHMENT FOR IGNITION APPARATUS.

1,414,753.

Specification of Letters Patent.

Patented May 2, 1922.

Application filed January 9, 1920. Serial No. 350,328.

To all whom it may concern:

Be it known that we, WOLFGANG E. SCHWARZMANN, a citizen of the United States, residing at and whose post-office address is 51 Belleclaire Avenue, Long Meadow, Hampden County, State of Massachusetts, and CLAYTON H. ALVORD, a citizen of the United States, residing at and whose post-office address is 28 Nelson Street, West Springfield, Hampden County, State of Massachusetts, have invented certain new and useful Improvements in Driving Attachments for Ignition Apparatus; and we do hereby declare the following to be a full, clear, and exact description of the invention, such as will enable others skilled in the art to which it appertains to make and use the same.

The present invention relates to driving attachments for driving from internal combustion engines, magnetos, and if desired distributors associated with the magnetos, to supply ignition current to the cylinders of the engine; and it relates particularly to attachments of that kind intended to be installed on existing engines of different types on automobiles or other moving vehicles, and on stationary engines.

Heretofore it was customary to use chains between sprocket wheels on the shafts of the magneto and engine at the front thereof, or to use gears on the shafts with or without intermediate gears, the gearing of either type being enclosed by a comparatively large housing extending around the shafts. Owing to the restricted and irregular space available at the front of the engine, each type of such attachment was devised with special reference to one particular type or model of engine, and owing to its size and shape, the attachment was comparatively heavy and expensive, besides requiring in some cases that the engine or auxiliaries therefor be machined to accommodate it, and in other cases that a considerable amount of fitting be done to secure it in place.

In accordance with our invention, the space requirement and weight of the attachment is reduced at a saving in cost, and the labor of the installation is reduced. We do this by combining with the engine and the magneto, or the magneto associated with a distributor, a rotatable drive shaft embodied in the mechanical connections between a

shaft of the engine and the shaft of the magneto, so that by using a longer or shorter drive shaft, as the case may require, the attachment, otherwise the same, may readily be installed on engines of different models or types.

Our invention comprehends, as one of its parts, an attachment which extends across the front of the engine and in which the rotatable drive shaft carries gears meshed with the gears on a shaft of the engine and the shaft of the magneto, each set of the cooperative gears being enclosed in a separate housing which, preferably, provides the bearings for the drive shaft. To further reduce the weight and space requirements and to provide more readily for different engines, the drive shaft is preferably unhoused, and the gears are of angle form, such as spiral, worm or bevel. Also the housing at the engine shaft may be secured in place by an arm, preferably a spring arm, fastened at one end to the engine and having its other end in engagement with or fastened to the housing, whereas the other housing may be secured to the magneto by fastening means.

While the foregoing arrangements provide for readily changing the length of the drive shaft to accommodate different engines, it is sometimes necessary also that the magneto be mounted in various relations to the engine, that is, at different elevations with respect to its crank case. Thus, whether or not the drive shaft carries gears in mesh with the respective gears on the shafts of the engine and magneto, and whether or not each set of cooperative gears is enclosed in a housing, our invention comprehends, as another of its parts, an attachment having a gear on a shaft of the engine, a gear on the magneto shaft, and angularly adjustable supporting means for supporting the drive shaft in adjusted axial position, so that it may extend between the gears in the direction that most suitably avoids existing parts of the engine and its auxiliaries. The adjustable supporting means may consist of a support attached to the magneto in adjusted position so as to be turned relatively to the magneto to accommodate the shaft in the axial direction in which it is to extend; or

the support attached to the engine may be secured thereto in adjusted position, so as to be turned to support the drive shaft in ad-

justed axial position; or both supports, the one at the shaft of the engine and also the one at the shaft of the magneto, may be attached in adjusted position so as to accommodate the drive shaft in the desired axial position. In the specific embodiments hereinafter disclosed, both supports are provided with angularly adjustable securing means, each preferably forming a housing as hereinbefore mentioned.

Where angle gearing is used, as shown in the preferred construction hereinafter disclosed, we have discovered that the engine knock that might otherwise occur may be prevented by relieving the shaft from end thrust of the attachment. In accordance with this part of our invention, the angle gear mounted on the shaft of the engine is arranged to thrust in the direction of said shaft, but a member secured to the engine has a bearing surface, such as a raised pad, against which said gear exerts its thrust.

Where the supports for the attachment are in the form of housings for the respective sets of cooperative gears, each of the gears on the drive shaft rotates against a bearing surface provided for it in the housing, so that the drive shaft is relieved of end thrust. Whether or not the end thrust on the drive shaft is relieved in this way, but preferably in combination with that construction, the drive shaft is arranged to float, as, for instance, by mounting the gears non-rotatably thereon but axially movable therealong. We have discovered that in this way the drive shaft is better able to withstand the shock and vibration to which it is subjected in operation, and can be made smaller than would otherwise be necessary for transmitting the fluctuating torque of the magneto. The advantages thereof are further enhanced by providing a bearing for the drive shaft, such as is formed by a collar fastened to the shaft and set into a bearing in one of the housings, or by fastening one of the gears to the drive shaft.

It is sometimes desirable to provide an auxiliary source of ignition for the engine. Where a distributor is used, the rotor may be connected to the drive shaft. For engines operating on the four-cycle stroke, thus requiring an ignition spark in each cylinder at alternate revolutions, the rotor of the distributor may be mounted directly on the outer end of the drive shaft, the drive shaft being geared to the engine to run at cam shaft speed, and also being geared to the magneto to drive it at the proper speed, such as crank shaft speed for a four-cylinder engine and a magneto generating two sparking voltages per rotation.

In the accompanying drawings illustrating our invention, in application, as examples, to various types of four-cylinder engines operating on the four-cycle stroke with

a bipolar magneto driven from the cam shaft, Fig. 1 is a front elevation of the attachment applied to the engine of a Ford automobile; Fig. 2 is a side elevation thereof; Fig. 3 is a front elevation of the attachment 70 as applied to an engine of a Fordson tractor; Fig. 4 is a side elevation thereof; Fig. 5 is a front elevation on an enlarged scale of the housing at the engine shaft of Fig. 1, with the cover removed; Fig. 6 is a front 75 elevation on the same enlarged scale of the housing at the magneto shaft of Fig. 1 with the cover removed; Figs. 7, 8 and 10 are sections on lines 7—7, 8—8 and 10—10, respectively, of Fig. 1; Fig. 9 is a section of 80 line 9—9 of Fig. 7; Fig. 11 is a section on line 11—11 on Fig. 6; and Fig. 12 is a front elevation, on another scale, of an attachment 85 for driving a magneto and a distributor from the engine, the covers of the housings being removed, and the electrical connections being shown diagrammatically.

Referring particularly to Figs. 1 and 2, the cam shaft 1 of the engine 2 is driven in anticlockwise direction by the crank shaft 3 90 through 1:2 speed reducing gearing (not shown). The oil well 4 is integral with the cover 5 of the gear case enclosing that gearing and bolted to the crank case 6. The belt adjuster 7 is fastened to the cover 5. 95

In Figs. 3 and 4, the cover 8 of the gear case is bolted to the crank case 9 of the engine 10, and encloses the gearing (not shown) between the crank shaft and the cam shaft to drive the cam shaft in anticlockwise 100 direction at half speed. The water duct 11 is integral with the cover 8, and the oil well 12 is located behind it.

The driving attachment illustrated in Fig. 1 is identical with that of Fig. 3, excepting 105 that the drive shaft 13 of Fig. 1 is shorter than the drive shaft 14 of Fig. 3, the attachment extending across the front of the engine and providing for different axial positions thereof to accommodate the magnetics 110 15 and 16 in different relations to the engine, as shown.

As shown particularly in Figs. 5 to 11, the attachment consists of a spiral gear 17 fast on the cam shaft 1 of the engine, and a spiral gear 18 fast on the armature shaft 19 of the magneto, the mechanical connections between them comprising the drive shaft 13 on which is non-rotatably secured a spiral 115 gear 20 in mesh with the gear 17 and a spiral 120 gear 21 in mesh with the gear 18. The spiral gear 17 is mounted fast by means of the split conical sleeve 22 forced between the cam shaft and an internal recess of the gear by the nut 23 and washer 24. The spiral gear 18 is fastened to the magneto shaft 19 by keying its tapered hub 25 to the shaft and holding it in position thereon by the nut 26 and washer 27. The gears 20 and 21 are each 125 non-rotatably secured to the drive shaft 13, 130

near opposite ends thereof, by the feathers 28 and 29 fast with the shaft and loosely set in slots of the respective gears, so that, although the shaft may move axially through 5 the gears, they turn with the shaft.

Each set of the cooperative or meshed gears 17, 20 or 18, 21 is enclosed in a separate housing. The housing at the cam shaft 1 of the engine consists of a rear member 10 30 and a cover 31 fastened together by screws along a plane axially of the drive shaft 13. The rear member 30 has a flanged back adapted to seat in the front member of the cover 5 of the gear casing, as shown in Fig. 15 7. It is also provided on its inner side with a raised pad 32 of annular form in sliding contact with the rear face 33 of the gear 17. Both the rear member and the cover of this 20 housing have recesses adapted, when the members are fastened together, to form cavities 34 and 35 for the gears 17 and 20, and 25 bearings 36 and 37 for the drive shaft 13. The grease cup 38 is intended to furnish lubrication for the gears and bearings within the housing.

The housing for the set of cooperative gears 18, 21 at the magneto shaft 19 comprises a rear member 39 and a cover 40 which likewise are screwed together along 30 a plane axially of the drive shaft 13. Each of these members is recessed so that when they are fastened there are cavities 41 and 42 for the gears 18 and 21, and bearings 43 and 44 for the drive shaft. Another cavity 35 45 is formed for the collar 46 which is pinned to the outer end of the drive shaft. The grease cup 47 is intended to furnish lubrication for the gears and the bearings within the housing.

40 The housing 30, 31 at the cam shaft 1 of the engine is secured in place by being held against the cover 5 of the gear casing by the spring arm 47' which is fastened at one end to the engine by the screw 48 and at the 45 other end to the cover 31 of the housing by the screw 49 passing through the slot 50 into the lug 51 of the cover. When the screw 49 is loosened, the housing 30, 31 may be turned about the cam shaft 1 through the 50 limit of the slot, and it may be fastened to the arm 47' at any adjusted position.

The rear member of the housing 39, 40 at the magneto shaft 19 has ears with elongated slots 52 for the screws 53 passing into the 55 bracket 54 which is rigidly fastened to the magneto. Upon loosening the screws 53, the housing may be turned about the magneto shaft through the limits of the slots 52, and the housing may be secured to the magneto in any adjusted position. Figs. 1 and 60 2 show the two housings fastened in adjusted position for supporting the drive shaft in one axial position, and Figs. 3 and 4 show the housings secured in another adjusted position to support the drive shaft in an axial 65

position more nearly horizontal. In both cases, the driving attachment avoids all parts of the engine and its auxiliaries without requiring any machining or fitting thereof.

As a result of the fact that the drive shaft 13 is axially slidable through the spiral gear's 20 and 21, although non-rotatably secured thereto, the end thrust of those gears is not transmitted to the drive shaft, but is taken up by the bearing surfaces provided by the cavities 35 and 42 in the housing. In this way the drive shaft merely floats, the end thrust to which it is subjected by reason of its weight and vibration or shock being taken up at the bearing for the collar 46 provided by the cavity 45 in the housing 39, 40.

The arrangement shown in Fig. 12 is similar in many respects to that of Figs. 1 and 2. However, the drive shaft 55 is extended so 20 as to have mounted on its outer end the rotor of the distributor 56 and the two housings 57 and 58 are modified to provide for such gears that the shaft is driven from the cam shaft of the engine without speed change, 25

whereas the magneto shaft is driven from the drive shaft through 2:1 speed-raising gears. In this way, the drive shaft 55 rotates at cam shaft speed, instead of crank shaft speed of the previous arrangements, to 30 provide the proper speed for the distributor. The magneto shaft rotates at crank shaft speed, as before. It will be observed that the housing at the cam shaft of the engine 2 provides cavities 61 and 62 for the 35 gears 63 and 64 and bearing surfaces at 65 and 66 for the drive shaft, whereas the housing at the magneto shaft 19 provides cavities 68 and 69 for the gears 70 and 71, and bearings 40 at 72 and 73 for the drive shaft. Also, the drive shaft has the collar 74 pinned to it in the cavity 75. The distributor 56 is 45 identical with that employed on engines existing on Ford cars, although rotated in opposite direction thereto, and, as is well known, is connected by wires 76 to vibrators in the coil box 77, the secondaries of which are connected to the spark plug cables 78. The distributor distributes the current from 50 the battery 79 to the vibrators in turn.

When the distributor is associated with the magneto, as shown in Fig. 12, and it is desired to replace magneto ignition with battery ignition, the spark plug cables 80 leading from the magneto are disconnected from 55 the spark plugs 81 and in place thereof the cables 78 are connected to the spark plugs. Upon closing the switch 82 to complete the circuit from the battery 79 to the vibrators, 60 ignition current is furnished from the auxiliary source in the order and at the time determined by the distributor.

In the arrangement of Fig. 1, the magneto 15 is mounted on a bracket 83 supporting the timing lever 84, whereas in the arrangement 130

of Figs. 3 and 4, the magneto 16 is mounted on a bracket 85 but, in this case, without a timing lever. In the arrangement of Fig. 12, the timing lever 86 concurrently times 5 the magneto and the distributor.

To install the magneto and the driving attachment therefor on the engine of Figs. 1 and 2, three bolts of the crank case 6 are removed, and longer bolts 87 and 88 substituted therefor to hold the magneto bracket 83 in place, after the radiator, fan attachment and timer are removed. The magneto 15 is then fastened on the base of the bracket. With the housing covers 31 and 40 detached, the rear members 30 and 39 are placed in position around the respective shafts 1 and 19. The gears 17 and 18 are then fastened on those shafts. When the members 31 and 40 are turned to the proper position, the drive shaft 13 is set in its bearings with the gears 20 and 21 in mesh with the gears 17 and 18. The covers 31 and 40 may then be attached to the rear housing member and the spring arm 47 secured to 25 the lug 51 in adjusted position. It is understood, of course, that the parts should have proper freedom and that the magneto should be timed properly to the engine.

The method of installing the arrangements of Figs. 3 and 12 will be obvious from the foregoing.

It is apparent that in all of the foregoing embodiments, the collar 46 and 74 may be omitted by fastening one of the gears on the drive shaft. The bearings for those gears would still relieve the drive shaft from end thrust, and the drive shaft, being axially movable through the other gear mounted on it, would still provide for slight variations 40 of the distance between the axes of the shaft of the magneto and the cam shaft of the engine, which variations might be due to inaccuracies in manufacture or installation, or to vibration in operation. Besides eliminating the collar, this arrangement also eliminates the bearing therefor and reduces the size and weight of that housing.

Having thus described our invention, what we claim is:

50 1. The combination with an internal combustion engine, and a magneto for supplying ignition current thereto, of a driving attachment arranged across the front of the engine for driving the magneto from the engine and comprising a gear on a shaft of the engine, a gear on the shaft of the magneto, a rotatable drive shaft carrying cooperative gears meshed with the respective gears on said shafts, a housing enclosing 55 the meshed gears at the shaft of the engine, and another housing enclosing the meshed gears at the shaft of the magneto, both of said housings providing bearings for the drive shaft.

65 2. The combination with an internal com-

bustion engine, and a magneto for supplying ignition current thereto, of a driving attachment arranged across the front of the engine for driving the magneto from the engine and comprising a gear on a shaft of the engine, a gear on the shaft of the magneto, a rotatable drive shaft carrying cooperative gears meshed with the respective gears on said shafts, a housing for the meshed gears at the shaft of the engine, an arm fastened 70 at one end to the engine and having its other end in engagement with said housing to hold it in place against the engine, another housing for the meshed gears at the shaft of the magneto, and fastening means for securing the last mentioned housing to the magneto.

3. The combination with an internal combustion engine, and a magneto for supplying ignition current thereto, of a driving attachment arranged across the front of the engine for driving the magneto from the engine and comprising a gear on a shaft of the engine, a gear on the shaft of the magneto, a rotatable drive shaft carrying cooperative gears meshed with the respective gears on said shafts, a housing for the meshed gears at the shaft of the engine, a spring arm fastened at one end to the engine 85 and fastened at the other end to said housing to hold it in place against the engine, another housing for the meshed gears at the shaft of the magneto, and fastening means for securing the last mentioned housing to the magneto.

4. The combination with an internal combustion engine, and a magneto adapted to be mounted in various relations to the engine for supplying ignition current thereto, of a driving attachment for driving the magneto from the engine, comprising a gear on a shaft of the engine, a gear on the shaft of the magneto, mechanical connections between said gears including a rotatable drive shaft, and angularly adjustable supporting means for supporting the drive shaft in adjusted axial position.

5. The combination with an internal combustion engine, and a magneto adapted to be mounted in various relations to the engine for supplying ignition current thereto, of a driving attachment for driving the magneto from the engine, comprising a gear on a shaft of the engine, a gear on the shaft of the magneto, a rotatable drive shaft, gears mounted on the drive shaft in engagement with the respective gears on the shafts of the engine and magneto, and angularly adjustable supporting means for supporting the drive shaft in adjusted axial position.

6. The combination with an internal combustion engine, and a magneto adapted to be mounted in various relations to the engine for supplying ignition current thereto, of a driving attachment for driving the magneto

- from the engine, comprising a gear on a shaft of the engine, a gear on the shaft of the magneto, mechanical connections between said gears including a rotatable drive shaft, 5 and an adjustable support secured to the magneto to support the drive shaft, and means for holding said support in adjusted position whereby said drive shaft is supported in adjusted axial position.
- 10 7. The combination with an internal combustion engine, and a magneto adapted to be mounted in various relations to the engine for supplying ignition current thereto, of a driving attachment for driving the magneto 70 from the engine, comprising a gear on a shaft of the engine, a gear on the shaft of the magneto, mechanical connections between said gears including a rotatable drive shaft, supports for the drive shaft, adjustable securing means for securing the support to the magneto in any position to which it may be turned, and adjustable securing means for securing the other support to the engine in any position to which it may be 75 turned, whereby the drive shaft is supported in adjusted axial position.
- 15 8. The combination with an internal combustion engine, and a magneto adapted to be mounted in various relations to the engine for supplying ignition current thereto, of a driving attachment for driving the magneto from the engine, comprising a gear on a shaft of the engine, a gear on the shaft of the magneto, mechanical connections between said gears including a rotatable drive shaft, a support adapted to be turned relatively to the magneto, and fastening means for securing the support to the magneto to support the drive shaft in adjusted axial 80 position.
- 20 9. The combination with an internal combustion engine, and a magneto adapted to be mounted in various relations to the engine for supplying ignition current thereto, of a driving attachment for driving the magneto from the engine, comprising a gear on a shaft of the engine, a gear on the shaft of the magneto, mechanical connections between said gears including a rotatable drive shaft, and an adjustable support attached to the engine to support the drive shaft, and 85 means for holding said support in adjusted position whereby said drive shaft is supported in adjusted axial position.
- 25 10. The combination with an internal combustion engine, and a magneto adapted to be mounted in various relations to the engine for supplying ignition current thereto, of a driving attachment for driving the magneto from the engine, comprising a gear on a shaft of the engine, a gear on the shaft of the magneto, mechanical connections between said gears including a rotatable drive shaft, a support adapted to be turned relatively to the engine, and means for securing the support to the engine to support the drive shaft in adjusted axial 90 position.
- 30 11. The combination with an internal combustion engine, and a magneto adapted to be mounted in various relations to the engine for supplying ignition current thereto, of a driving attachment for driving the magneto from the engine, comprising a gear on a shaft of the engine, a gear on the shaft of the magneto, a rotatable drive shaft having gears mounted on it in mesh with the respective gears on the shafts of the engine and magneto, a housing enclosing the meshed gears at the engine shaft, and a housing enclosing the meshed gears at the magneto 95 shaft, one of said housings having securing means for holding it in adjusted position to thereby support the drive shaft in adjusted axial position.
- 35 12. The combination with an internal combustion engine, and a magneto adapted to be mounted in various relations to the engine for supplying ignition current thereto, of a driving attachment for driving the magneto from the engine, comprising a gear on a shaft of the engine, a gear on the shaft of the magneto, a rotatable drive shaft having gears mounted on it in mesh with the respective gears on the shafts of the engine and magneto, a housing enclosing the meshed gears at the engine shaft, and a housing enclosing the meshed gears at the magneto shaft, one of said housings having securing means for holding it in adjusted position to thereby support the drive shaft in adjusted axial 100 position.
- 40 13. The combination with an internal combustion engine, and a magneto adapted to be mounted in various relations to the engine for supplying ignition current thereto, of a driving attachment for driving the magneto from the engine, comprising a gear on a shaft of the engine, a gear on the shaft of the magneto, a rotatable drive shaft having gears mounted on it in mesh with the respective gears on the shafts of the engine and magneto, a housing enclosing the meshed gears at the engine shaft, and a housing enclosing the meshed gears at the magneto shaft, each of said housings having securing means for holding it in adjusted angular 105 position to thereby support the drive shaft in adjusted axial position.
- 45 14. The combination with an internal combustion engine, and a magneto for supplying ignition current thereto, of a driving attachment for driving the magneto from the engine, comprising a gear on a shaft of the engine, a gear on the shaft of the magneto, and mechanical connections between said gears including a floating drive shaft.
- 50 15. The combination with an internal combustion engine, and a magneto for supplying ignition current thereto, of a driving attachment for driving the magneto from the engine, comprising a gear on a shaft of the engine, a gear on the shaft of the magneto, 110 and mechanical connections between said gears including a floating drive shaft.
- 55 60 16. The combination with an internal combustion engine, and a magneto for supplying ignition current thereto, of a driving attachment for driving the magneto from the engine, comprising a gear on a shaft of the engine, a gear on the shaft of the magneto, and mechanical connections between said gears including a floating drive shaft.
- 65 17. The combination with an internal combustion engine, and a magneto for supplying ignition current thereto, of a driving attachment for driving the magneto from the engine, comprising a gear on a shaft of the engine, a gear on the shaft of the magneto, and mechanical connections between said gears including a floating drive shaft.

- neto, cooperative gears meshed with the gears on said shafts, a rotatable drive shaft non-rotatably secured to said cooperative gears and axially movable through one 5 thereof, and means preventing axial movement of the drive shaft.
16. The combination with an internal combustion engine, and a magneto for supplying ignition current thereto, of a driving attachment for driving the magneto from the engine, comprising a gear on a shaft of the engine, a gear on the shaft of the magneto, cooperative gears meshed with the gears on said shafts, a rotatable drive shaft non-rotatably secured to said cooperative gears and axially movable therethrough, and means for preventing axial movement of the drive shaft.
17. The combination with an internal combustion engine, and a magneto for supplying ignition current thereto, of a driving attachment for driving the magneto from the engine, comprising an angle gear on a shaft of the engine, an angle gear on the shaft of the magneto, cooperative angle gears meshed with the gears on said shafts, a rotatable drive shaft non-rotatably secured to said cooperative gears and axially movable therethrough, and a collar fast with the drive shaft and arranged to prevent axial movement thereof.
18. The combination with an internal combustion engine, and a magneto for supplying ignition current thereto, of a driving attachment for driving the magneto from the engine, comprising an angle gear mounted on a shaft of the engine and arranged to thrust in the direction of said shaft, a member secured to the engine and having a bearing surface against which said gear thrusts, and a driving connection between said gear and the shaft of the magneto.
19. The combination with an internal combustion engine, and a magneto for supplying ignition current thereto, of a driving attachment for driving the magneto from the engine, comprising an angle gear mounted on a shaft of the engine and arranged to thrust in the direction of said shaft, a member secured to the engine and having a raised pad against which said gear thrusts, and a driving connection between said gear and the shaft of the magneto.
20. The combination with an internal combustion engine, and a magneto for supplying ignition current thereto, of a driving attachment for driving the magneto from the engine, comprising an angle gear on a shaft of the engine, an angle gear on the shaft of the magneto, mechanical connections between said gears including a rotatable drive shaft carrying cooperative gears meshed with the gears on said shafts, and a housing enclosing each of said cooperative gears and having a bearing surface arranged to take the end thrust thereof.
21. The combination with an internal combustion engine, and a magneto supplying ignition current thereto, of a driving attachment for driving the magneto from the engine, comprising an angle gear on a shaft of the engine, an angle gear on the shaft of the magneto, mechanical connections between said gears including a rotatable drive shaft non-rotatably secured to but axially movable through cooperative gears meshed with the gears on said shafts, and a housing enclosing each of said cooperative gears and having bearing surfaces arranged to take the end thrust thereof.
22. The combination with an internal combustion engine, a magneto for supplying ignition current thereto, and a distributor for supplying ignition current thereto from an auxiliary source of current, of a driving attachment for driving the magneto and the distributor from the engine, comprising a gear on a shaft of the engine, a gear on the shaft of the magneto, and a rotatable shaft carrying cooperative gears meshed with the respective gears on said shafts and also carrying the rotor of the distributor.
23. The combination with an internal combustion engine operating on the four-cycle stroke, a magneto for supplying ignition current thereto, and a distributor for supplying ignition current to the engine from an auxiliary source of current, of a driving attachment for driving the magneto and the distributor from the engine, comprising a drive shaft driven by the engine at cam shaft speed and secured to the rotor of the distributor, and gearing between the drive shaft and the magneto for driving the magneto at the proper speed to produce one ignition current for each cylinder at alternate revolutions of the engine.
24. The combination with a four-cylinder internal combustion engine operating on the four-cycle stroke, a bipolar magneto for supplying ignition current thereto, and a distributor for supplying ignition current to the engine from an auxiliary source of current, of a driving attachment for driving the magneto and the distributor from the engine, comprising a drive shaft driven by the engine at cam shaft speed and secured to the rotor of the distributor, and gearing between the drive shaft and the magneto for driving the magneto at crank shaft speed.

In testimony whereof we hereto affix our signatures.

WOLFGANG E. SCHWARZMANN.
CLAYTON H. ALVORD.
